INCLINED SHAFT MUCKING APPARATUS

Leonard J. Bares, San Leandro, Calif., assignor to Foley Brothers Inc., a corporation of New York

Application March 5, 1954, Serial No. 414,412

8 Claims. (Cl. 214—90)

This invention relates to apparatus for the removal of muck from the bottom of an inclined shaft. The new apparatus comprises, in combination, an improved mucking bucket, a skip for hauling the ore up the shaft, and a pan car for transferring muck from the mucking bucket to the skip. 15

Many devices have been developed heretofore to assist in the rapid and efficient removal of muck from the bottom of a mine shaft and from the working face of other underground openings. The most successful mechanical mucking devices for underground use that have heretofore been developed are particularly suited for mucking either from the bottom of a vertical or nearly vertical shaft, or from the working face of a horizontal or only slightly inclined tunnel or drift. Not infrequently, however, mine shafts and other underground openings must be driven in directions that are inclined too steeply from the horizontal to permit effective use of mucking devices intended to operate mainly on horizontal surfaces, and that also are inclined enough from the vertical so that conventional vertical shaft mucking devices cannot be used efficiently. The present invention provides an improved combination of apparatus which is especially suited for efficient mechanical handling and removal of muck from the bottom of such inclined shafts. 25

The new mucking apparatus comprises three major components, (1) a mucking bucket assembly by which muck is excavated from the muck pile at the bottom of the shaft, (2) a skip by which the muck is hoisted out of the shaft, and (3) a pan car by which the muck excavated by the mucking bucket is transferred therefrom to the skip. A particularly advantageous combination according to the invention comprises an overhead monorail secured adjacent the hanging wall of the shaft, and extending up the shaft from the bottom thereof. A crawl assembly is supported on the monorail and is arranged to be driven therealong. A rigid downwardly extending arm is pivotally connected at one end to the crawl assembly, and a mucking bucket is connected (preferably pivotally) to the other end of the arm. Power means are provided for driving the crawl on the monorail, and power means are provided to pivot the bucket on the arm and to pull the bucket and arm upwardly. A narrow gauge track extends substantially the full length of the shaft along the footwall thereof, and a skip for hoisting muck up the shaft rides on such track. An elevated ramp, comprising a relatively wide gauge track, is positioned a substantial distance up the shaft from the bottom thereof, said ramp being arranged so that it straddles the narrow gauge track and extends thereabove sufficiently to permit the skip to pass under it. A pan car having a releasable bottom closure and having wheels for riding both on said narrow gauge track and on said wide gauge track is arranged for travel between the lower end of the narrow gauge track and the ramp; and a hoist is provided for pulling the pan car up the elevated ramp from a position therebelow on the narrow gauge track underlying the monorail. 35

The above-described combination of apparatus thus is

2

such that muck excavated from the muck pile by the mucking bucket may be transferred from the mucking bucket to the pan car, the pan car may then be hoisted up the ramp, the skip may then be lowered under the pan car, and the muck may then be transferred through the releasable bottom of the pan car into the skip for hoisting up the shaft. 5

The foregoing and other features of the new apparatus are described in greater detail below in conjunction with 10 the accompanying drawings showing a preferred embodiment of the invention, and in which

Fig. 1 is an elevation showing the mucking bucket and the pan car of the new shaft mucking apparatus, in operating position at the bottom of an inclined shaft;

Fig. 2 is a view of that portion of the combination of apparatus which is installed in the shaft a substantial distance above the bottom thereof (Fig. 2 is drawn so that when the line B—B of Fig. 2 is superimposed on the line A—A of Fig. 1, Fig. 2 forms an extension of Fig. 1); 20

Fig. 3 is an elevation of the mucking bucket assembly; Fig. 4 is a plan of the mucking bucket and its supporting arm;

Fig. 5 is a sectional view taken substantially along the line 5—5 of Fig. 1, showing the manner in which the mucking bucket assembly is supported; 25

Fig. 6 is an elevation of the pan car;

Fig. 7 is a rear elevation of the pan car, taken substantially along the line 7—7 of Fig. 1; and

Fig. 8 is a section through the shaft, taken substantially 30

along the line 8—8 of Fig. 2, showing the pan car supported on the ramp.

Figs. 1 and 2 show an inclined mine shaft 10 which is being driven downwardly at a substantial angle to both the vertical and horizontal directions by breaking rock at 35

the bottom and excavating the broken rock from the muck pile 11. As the shaft is advanced, timber sets comprising framing timbers 12 and stringers 13 are installed to support the ground. These timbers additionally are employed to support various elements of the mucking apparatus. 40

The mucking apparatus itself comprises the combination of a mucking bucket assembly 14 (Fig. 1), a pan car 15 (Fig. 1), a ramp 16 (Fig. 2), and a skip 17 (Fig. 2). Briefly stated, operation of the apparatus involves excavating 45

muck from the muck pile 11 by means of the bucket assembly 14, delivering the muck from the bucket assembly to the pan car 15, then hoisting the pan car up the ramp 16 so that the skip 17 can be lowered under it, and then transferring the muck from the pan car to the skip for hoisting up the shaft. 50

The mucking bucket assembly 14 is supported on an I-beam monorail 18. The I-beam is secured adjacent the hanging wall of the shaft to the hanging wall frame timbers 12, by means of brackets 19. Each bracket comprises a base plate 20 (Fig. 5) which is fastened to the timber 12 by bolts 21 passing alongside the timbers and through straps 22 which span the timber. Shim plates 23 and supporting plates 24 are welded or otherwise securely attached to the base plates 20. The shim plates 23 are 55

spaced apart a distance slightly greater than the width of the upper flange of the I-beam 18, and the supporting plates 24 are spaced apart a distance somewhat greater than the thickness of the web of the I-beam, and are bent to conform to the slightly sloping inside surface of the I-beam upper flange. The brackets securely anchor the I-beam monorail 18 to the hanging wall frame timbers, but it will be noted that there is a substantial clearance about the periphery of the I-beam flange. The lower end of the I-beam monorail simply rests against the muck pile 60 at the bottom of the shaft. As this muck pile is excavated, the monorail is allowed to slide downwardly, and in this manner it is readily advanced as the shaft is deep- 65

ened. Similarly, when it is necessary to blast to break the rock at the bottom of the shaft, the I-beam can be pulled up the shaft, in its suspending brackets, to a safe distance, and can be easily and quickly returned to its normal operating position thereafter.

The mucking bucket assembly comprises a crawl 25, which in turn comprises a pair of dolly assemblies 26 and 27 held in spaced relation by longitudinal frame bars 28. As best shown in Figs. 3 and 5, each dolly assembly comprises a pair of T-shaped side plates 29. The plates 29 are held in correct spaced relation and are secured to the longitudinal frame bars 28 by a shaft 30. Two pairs of rollers 31 are secured to the frame plates in position to ride on the inner surface of the lower flange of the I-beam monorail 18; and a pair of stabilizing rollers 32 are mounted on the shaft 30 in position to bear against the underside of the I-beam lower flange.

The crawl 25 is advanced up and down the monorail 18 by a tugger hoist 33 (Fig. 1) mounted on the monorail near its upper end. A crowd chain 34 passes around a drive sprocket 35 on the tugger, and around an idling sprocket 36 attached to the forward end of the I-beam monorail; and the two ends of this chain are anchored respectively to the fore and aft dolly assemblies 26 and 27 of the crawl. Rotation of the drive sprocket 35 in a clockwise direction, as viewed in Fig. 1, advances the crawl down the monorail toward the muck pile, and rotation of the drive sprocket in the opposite direction moves the crawl up the monorail.

A mucking bucket 37 is pivotally attached through a rigid arm 38 to the aft crawl dolly 27. The arm 38 comprises a pair of diverging members 39 which at one end are welded to a pivot plate 40 that is pivotally mounted on the dolly shaft 30. At their diverging ends, the members 39 are attached to a spreader 41 and to a pair of bucket pivot plates 42. The mucking bucket 37 comprises a pair of side plates 43, and a bottom plate 44. The forward end of the bottom plate is shaped to provide a digging lip 46, and the rearward end portion 47 of this plate is curved upwardly and thence forwardly to form a closed back for the bucket. The bucket side plates 43 are pivotally mounted, by pins 48, between the pivot plates 42. The point of this pivotal mounting is preferably slightly below and to the rear of the center of gravity of the bucket, so that through the force of gravity the digging lip of the bucket tends to tilt down about the axis of the pins 48. Sometimes, however, it is desirable to lock the bucket 37 against such pivotal motion, and for this purpose at least one of the plates 42 is provided with a hole 50 and an aligned hole 51 is formed in the corresponding bucket side plate 43. By inserting a pin through these holes when they are in alignment, the bucket is securely locked against pivotal movement in the arm 38.

A bail 52 is secured to the side plates 43 of the mucking bucket, adjacent the digging lip 46. The bail carries a sheave 53, about which a hoisting cable 54 is passed. One end of this hoisting cable is anchored to the forward crawl dolly 26. The other end of the cable is passed over an idling sheave 55 carried by this same dolly, thence under a similar idling sheave 56 carried by the aft crawl dolly 27, and thence to a capstan or winding drum 58 of a second tugger hoist 59. By winding the hoist cable 54 on to the drum 58, the mucking bucket may be tilted about its pivotal mounting in the supporting arm 38, and may be lifted with accompanying pivotal movement of the arm 38 on the dolly shaft 30, from the position shown in full lines to position I shown in dotted lines at the lower end of Fig. 1. By appropriate manipulation of the crawl tugger 33 and the bucket manipulating tugger 59, it is easily possible to fill the mucking bucket with broken rock from the muck pile 11, and to lift the filled bucket to an elevated position.

The muck picked up by the bucket 37 is hoisted up the shaft in the skip 17 (Fig. 2). The skip is of more

or less conventional design for operation in an inclined shaft. It comprises a rectangular bucket-like body 60, open at its upper end 61, and mounted on flanged wheels 62. The skip rides on a narrow gauge track comprising a pair of parallel rails 63 conventionally laid adjacent the footwall on the footwall frame timbers 12. A hoist cable 64, attached to the skip bail 65, extends up the shaft to a skip hoist (not shown) at the head of the shaft.

The rails 63 forming the narrow gauge skip track extend substantially to the bottom of the shaft, and the pan car 15, by which muck is transferred from the mucking bucket 37 to the skip 17, is adapted to ride thereon. The pan car (Figs. 6 and 7) comprises a box-like body 70 having a releasable bottom closure 71 hingedly attached thereto. The pan car is supported on the rails 63 by means of small flanged wheels 72 rotatably mounted on axles 73. The axles 73 extend considerably beyond the span of the narrow gauge track, and carry additional flanged wheels 74 at their outer ends, for engagement with a relatively wide gauge track on the ramp 16 (Fig. 2).

The ramp 16 is formed by a pair of steel channels 75, which have been bent edgewise, as shown in Fig. 2, and which are mounted parallel to each other and spaced apart so that their flanges face toward each other, as shown in Fig. 8. The channels 75 are held in place and braced by supporting frame members 76, which in turn are detachably secured to the frame timbers 12. The channels 75 form the wide gauge track on which the outboard wheels 74 of the pan car ride, and they are accordingly spaced apart a distance corresponding to the spacing of the wheels 74. The width of the channels, between the inside surfaces of the flanges thereof, is slightly greater than the diameter of the approximately cylindrical riding surface of the wheels 74. The wheels 74 of the pan car ride on the inside surface of the lower flanges of the spaced channels 75, and are prevented from shifting laterally or upwardly by the webs and upper flanges of the channel. The upper flange of each channel is cut away, as indicated at 77 in Fig. 2, where the ramp slopes down to the level of the narrow gauge track formed by the rails 63. When the pan car is pulled up the rails 63, the outboard wheels 74 thereof, upon arriving at the lower end of the ramp, enter between the flanges of the channels 75 at the cut-away part 77, and thereby the pan car is lifted off the rails 63 and up the ramp.

The pan car is connected by a hoist cable 78 to the drum 79 of a tugger hoist 80 mounted at the upper end of the ramp 16. The cable 78 is connected to the pan car by being passed through a small opening in the hinged bottom closure 71, around a bar 81, to a point where its end is anchored to the closure 71 by cable clamps 82. It will be noted that by this arrangement the bottom closure of the pan car is held closed so long as the cable 78 remains taut, which, of course, it does so long as the weight of the car and its contents is carried by the cable. At the forward end of the pan car, the cable 78 passes through a U-shaped guide 83 which is pivotally connected to the body of the pan car.

Operation of the above-described apparatus is as follows: When the rock at the bottom of the shaft has been broken to form the muck pile 11, and when the apparatus has been set in position as described above, muck is excavated from the pile by operation of the tuggers 33 and 59 to crowd the mucking bucket 37 into the muck and to hoist the bucket, when full of muck, to the elevated position I shown in dotted lines in Fig. 1. Then the two tuggers 33 and 59 are operated to move the crawl 25 up the monorail, without lowering the mucking bucket, to position II shown in dotted lines in Fig. 1. Next, with the pan car 15 in the position shown in Fig. 1, the mucking bucket 37 is lowered and allowed to pivot downwards to position III shown in dotted lines in Fig. 1, so as to discharge its contents by gravity flow into the pan car. In doing so, the pan car hoist cable 78 may be pressed

downwardly to the position indicated in dotted lines, and the guide 83 may be tilted out of the way, by the weight of the mucking bucket.

The capacity of the pan car may be about equal to the capacity of the skip, or it may require two or more pan car loads to fill the skip, but in any event the pan car is generally large enough to require several mucking bucket loads to fill it. Hence, after the above-described sequence of operations, the mucking bucket is returned to the muck pile for another load of muck, while the pan car remains in the position shown in Fig. 1.

After the pan car has been filled, the hoist tugger 80 is operated to pull the pan car up the ramp to the position indicated in solid lines in Fig. 2. Then the skip 17 is lowered down the narrow gauge track, under the pan car 15 and between the channels 75 of the ramp, to the position shown in dotted lines. It will be noted that in this position the skip is directly in the path of travel of the pan car on the ramp. The tugger 80 is then reversed and the pan car is lowered down the ramp until, in the position shown in dotted lines in Fig. 2, it rests against the open upper end of the skip. The bottom closure 71 of the pan car is a little narrower than the body of the skip, and consequently, as the tugger 80 is operated to slack off on the cable 78, the weight of the muck in the pan car causes the bottom closure 71 to swing open, permitting the muck to flow into the skip. When the muck has thus been transferred from pan car to skip, the pan car is once again pulled up the ramp about to the position shown in solid lines, and the skip is thereupon hoisted up the shaft. While the skip is making the trip up the shaft and back down again after it has been emptied, the pan car is lowered again to the position shown in Fig. 1, and excavation of muck, and reloading of the pan car, proceeds as described above.

It will be noted that the apparatus described above is eminently suitable for operation in shafts that are inclined through a wide range of angles. It is particularly suited for operation in shafts inclined at an angle in the range from 30° to 75° from the horizontal. This is the range through which mechanical muckers designed for operation in horizontal drifts, and mucking apparatus for sinking vertical shafts, are both impractical to use.

Features additional to those described above can be incorporated in the apparatus to facilitate handling it in normal shaft sinking operations. For example, it is advantageous to attach a bracket 85 (Figs. 3 and 4) carrying a sheave 86 to the spreader 41 of the mucking bucket arm. Such sheave may be used in place of the bail 52 and sheave 53 to hoist the bucket 37 and arm 38, when these two members are locked together by a pin extending through the aligned holes 50 and 51. Alternatively, a separate cable can be passed around the sheave 86 to an additional tugger hoist drum, so that hoisting of the arm 38 and pivotal rocking of the bucket 37 on the arm can be separately and independently controlled.

It is also advantageous to provide a pair of brackets 87 (Fig. 3) projecting from the frame members 28 of the crawl. These brackets are formed at their lower ends with aligned holes 88; and when the bucket arm is hoisted to a position parallel with the crawl frame bars 28, it can then be suspended in such position by inserting a bar through the holes 88. In this manner, the mucking bucket and arm can conveniently be held close against the hanging wall of the shaft, in a position where it is out of the path of travel of the skip 61.

It will be noted that the monorail 18, on which the mucking bucket crawl 25 travels, is easily advanced as the shaft is deepened, and as new frames of timbers 12 are installed, by simply allowing it to slide down through the hanging brackets by which it is mounted. Additional lengths of the rails 63 are laid, as required by deepening of the shaft, so that the pan car 15 can always be lowered sufficiently to be within reach of the operating range of the mucking bucket assembly. At such less frequent intervals as are most convenient, the sup-

porting frame members 76 of the ramp 16 may be loosened from the sets of timbers to which they are attached, and the entire ramp may be lowered down the shaft.

While it is desirable to have the ramp 16 fairly close to the bottom of the shaft, so as to minimize the distance through which the pan car must be hoisted, it is an advantage of the apparatus described above that there is nothing critical about the proximity of the ramp to the bottom of the shaft, and it is quite unnecessary to lower it down the shaft every time new lengths of rails 63 are laid in place.

Although the new apparatus is illustrated in the drawings as it would be used in a single compartment shaft, it can equally well be used in sinking a shaft of two or more compartments.

I claim:

1. In apparatus for the removal of muck from the bottom of an inclined shaft having ground supporting members set against the hanging wall of said shaft, a monorail secured to said members and held thereby adjacent the hanging wall of the shaft and extending up the shaft from the bottom thereof, a crawl assembly supported on the monorail and adapted to be driven therealong, a rigid downwardly extending arm pivotally connected at one end to the crawl assembly, a mucking bucket pivotally connected to the other end of said arm, means for driving the crawl on the monorail, and means for pivoting the bucket on said arm and for pulling the bucket and arm to a position adjacent to the crawl, said crawl driving means and said bucket pivoting means being supported adjacent the hanging wall of the shaft, whereby the entire mucking bucket assembly may be elevated from the shaft foot wall and a car for carrying muck may be lowered thereunder into position to receive muck from the mucking bucket.

2. In apparatus for the removal of muck from the bottom of an inclined shaft, a monorail secured adjacent the hanging wall of the shaft and extending up the shaft from the bottom thereof, a crawl assembly supported on the monorail and adapted to be driven therealong, a rigid downwardly extending arm pivotally connected at one end to the crawl assembly, a mucking bucket having side members and a digging lip and being pivotally connected to said arm, a U-shaped bail connected to the bucket adjacent the digging lip and forwardly of the pivot point of the bucket and arm, means for driving the crawl assembly on the monorail, and means engaging the bail of said bucket to pivot the bucket on said arm and to pull the bucket and arm upwardly.

3. In apparatus for the removal of muck from the bottom of an inclined shaft, a monorail secured adjacent the hanging wall of the shaft and extending up the shaft from the bottom thereof, a crawl assembly supported on the monorail and adapted to be driven therealong, a rigid downwardly extending arm pivotally connected at one end to the crawl assembly and forked at its other end, a mucking bucket having side members and a digging lip pivotally mounted in the forked end of said arm on an axis passing somewhat below the center of gravity of the bucket, a U-shaped bail pivotally connected at each end to a side member of the bucket adjacent the digging lip thereof, means for driving the crawl on the monorail, and means engaging the bail of said bucket to pivot the bucket on said arm and to pull the bucket and arm upwardly.

4. In apparatus for the removal of muck from the bottom of an inclined shaft having supporting timbers set against its hanging wall, an aligned row of monorail support brackets secured to the undersides of said timbers, a monorail suspended by said brackets, and a crawl assembly including a mucking bucket suspended from the monorail and adapted to be driven therealong, said monorail resting against the bottom of the mine shaft and being slidably supported by said brackets to permit longitudinal movement of the monorail and crawl assembly as a unit in the brackets.

5. In apparatus for the removal of muck from the bottom of an inclined shaft, the combination comprising an overhead monorail secured adjacent the hanging wall of the shaft and extending up the shaft from the bottom thereof, a crawl assembly supported on the monorail and adapted to be driven therealong, a rigid downwardly extending arm pivotally connected at one end to the crawl assembly, a mucking bucket connected to the other end of said arm, means for driving the crawl assembly on the monorail, means to pull the bucket and arm upwardly, a narrow gauge track extending substantially the full length of the shaft along the footwall thereof, a skip riding on said narrow gauge track, an elevated ramp comprising a relatively wide gauge track positioned a substantial distance up the shaft from the bottom thereof, said ramp straddling the narrow gauge track and extending thereabove sufficiently to permit the skip to pass thereunder, a pan car having a releasable bottom closure and having wheels for riding both on said narrow gauge track and on said wide gauge track, and a hoist for pulling the pan car up the elevated ramp from a position therebelow on the narrow gauge track underlying the monorail, whereby muck may be transferred from the mucking bucket to the pan car, the pan car may then be hoisted up the ramp, the skip may then be lowered under the pan car, and the muck may then be transferred from the pan car to the skip for hoisting up the shaft.

6. Apparatus in accordance with claim 5, characterized in that said wide gauge track comprises a pair of channel irons having their flanges extending inwardly, and the wheels of said pan car adapted to ride on said wide gauge track are of a diameter slightly less than the space between the flanges of said channel irons.

7. Apparatus in accordance with claim 5, characterized in that said pan car is provided with a box-like body having a releasable bottom closure pivotally connected thereto, and in that a flexible hoist cable by which said pan

car is connected to the pan car hoist is secured to said closure and extends forwardly therefrom through the pan car body, whereby said bottom closure is maintained closed so long as the weight of the pan car is supported by said cable, but is released when said cable is slackened off relatively to the pan car.

8. In apparatus for the removal of muck from an inclined shaft, the combination comprising a narrow gauge track extending substantially the full length of the shaft along the footwall thereof, a skip riding on said narrow gauge track, an elevated ramp comprising a relatively wide gauge track positioned a substantial distance up the shaft from the bottom thereof, said ramp straddling the narrow gauge track and extending thereabove sufficiently to permit the skip to pass thereunder, a pan car having a releasable bottom closure and having wheels for riding both on said narrow gauge track and on said wide gauge track, and a hoist for pulling the pan car up the elevated ramp from a position therebelow on the narrow gauge track adjacent the bottom of the shaft, whereby when said pan car has been loaded with muck adjacent the bottom of the shaft, it may then be hoisted up the ramp, the skip may then be lowered under the pan car, and the muck may then be transferred from the pan car to the skip for hoisting up the shaft.
